UNITED STATES PATENT OFFICE

ARTHUR GARRETSON, OF PLYMOUTH, PENNSYLVANIA

DESIGN FOR AN EASY CHAIR RADIO REMOTE CONTROL

Application filed July 29, 1931. Serial No. 40,716. Term of patent 7 years.

To all whom it may concern:

Be it known that ARTHUR GARRETSON, a citizen of the United States of America, residing at Plymouth, in the county of Luzerne and State of Pennsylvania, has invented a new, original, and ornamental Design for an Easy Chair Radio Remote Control, of which the following is a specification, reference being had to the accompanying drawings, forming part thereof.

Figure 1 is a top plan view of my easy chair radio remote control, the balancing strap being partly broken away, and

Figure 2 is a side view of Figure 1.

Having thus set forth and disclosed the nature of this invention, what is claimed is:

The ornamental design for an easy chair radio remote control, as shown.

In testimony whereof I affix my signature.
ARTHUR GARRETSON.
